UNITED STATES PATENT OFFICE.

FREDERICK C. OVERBURY, OF MONTCLAIR, NEW JERSEY, ASSIGNOR TO FLINTKOTE MANUFACTURING COMPANY, OF RUTHERFORD, NEW JERSEY, A CORPORATION OF NEW JERSEY.

SHINGLE-STRIP.

1,150,298.

Specification of Letters Patent.

Patented Aug. 17, 1915.

Application filed March 1, 1915. Serial No. 11,392.

To all whom it may concern:

Be it known that I, FREDERICK C. OVERBURY, a citizen of the United States, and a resident of Montclair, in the county of 5 Essex and State of New Jersey, have invented certain new and useful Improvements in Shingle-Strips, of which the following is a specification.

This invention has relation to prepared 10 waterproof weatherproof coverings for roofs and side walls, which, when laid, present the appearance of shingles or tiles.

Prepared roofing usually consists of a sheet of felt or similar fibrous material impregnated or saturated with some waterproofing composition, and having on one or both faces a layer of pitch, asphalt, or the like, in which is frequently embedded crushed mineral material. In such sheets, 15 the fibers composing the felt in the main extend generally longitudinally of the sheet, and, when the roof covering is exposed to the action of the elements, it tends to expand and contract crosswise of the sheet or 20 of the general direction of the fibers.

I have found that, by cutting the sheet crosswise into strips and forming the shingle-like or tile-like projections thereon, to extend in the general direction of the fibers, 25 I am able to prevent any material bending or buckling of the strips and the tabs thereof when laid.

Hence the present invention consists, as a new article of manufacture, of a shingle strip formed of waterproof roofing felt having along its lower edge spaced tabs or projections of any suitable configuration which extend longitudinally of the fibers of the 30 felt. These strips, when laid in overlapping rows to expose said tabs or projections, present the appearance of a shingle or tile roofing.

On the accompanying drawing,—Figure 1 illustrates a sheet of prepared fibrous material and shows how the shingle strips may be formed therefrom. Fig. 2 illustrates one of the shingle strips. Fig. 3 shows a shingle strip having different shaped tabs. Fig. 4 represents a section on the line 4—4 of 40 Fig. 2 on a larger scale.

In the manufacture of wool felt, such as I employ for the foundation of my roof covering, the fibers are in the main arranged longitudinally of the length of the strip or 45 sheet, and, in accordance with the present

invention, the shingle strips are cut from the sheet along lines transverse to the longitudinal lines of the sheet so that each strip, although it is provided with a plurality of tabs or projections which when laid form 60 the appearance of tiles or shingles, are relatively short, and, because of the arrangement of the fibers transversely of the length thereof, do not bend and buckle when exposed to varying thermal and weather conditions. The foundation of the strip consists of such wool felt which is saturated or impregnated with the usual waterproofing composition employed in the manufacture of prepared weatherproof roofing, such as 65 pitch, asphalt and the like. The sheet of felt, after being impregnated and saturated with waterproofing compound, is then coated on one or both faces with a weatherproofing coating such as asphalt or pitch of 70 such consistency that it will not run when exposed to solar heat. In some cases, the coating on the outer face of the sheet has embedded therein any suitable mineral material, such as ground or crushed slate or, 75 granite or sand, the embedment occurring while the coating is in a soft and plastic state.

In Fig. 4, the impregnated felt is indicated at *a*, the coatings of weatherproof material are indicated at *b* and *c*, and the layer of pressed mineral material is indicated at *d*. After an elongated sheet of suitable width has been thus prepared, it is ready for further treatment in accordance with my invention. Between the side edges of the sheet *e*, I may form, by any suitable instrumentalities, a series of pairs of longitudinal slits *f*, *g* which may be spaced apart say for example $\frac{1}{2}$ inch. These slits extend longitudinally of the sheet and are formed in a row across the sheet as shown in Fig. 1. What may be termed the rear ends of the slits are connected by a cross-slit *h*, so that there are formed a series of rearwardly extending 90 tongues *i* which are connected at their front ends to the main body of the sheet. These rows of tongues are separated, longitudinally of the sheet, by a distance of say 7 to 95 10 inches more or less as circumstances may require. Then, by any suitable cutting tool or other instrumentality, the sheet is severed on the dotted line *j*, *j* in Fig. 1, the said line coinciding with the forward ends of the slits *f*, *g*. As a result of this procedure, there is 105 110

formed a series of shingle strips *k*, each of which is formed at its front or lower edge with a series of tabs or projections *m* separated by slots *n*, with a straight edge *o* defining its upper or rear end. Any other method, however, may be followed in forming the strips from the sheet to secure the desired formation of tabs or projections. In these strips, the fibers of the impregnated 5
